UNITED STATES PATENT OFFICE.

ROSCOE BEAN, OF BEREAL, OHIO.

TOY PISTOL.

1,098,215.

Specification of Letters Patent. Patented May 26, 1914.

Application filed January 20, 1914. Serial No. 813,191.

To all whom it may concern:

Be it known that I, ROSCOE BEAN, a citizen of the United States, residing at Berea, in the county of Cuyahoga and State of Ohio, have invented certain new and useful Improvements in Toy Pistols, of which the following is a specification.

My invention relates to improvements in toy pistols, and more particularly to that class or type known as "repeating toy pistols" in which a series of percussion caps are arranged in a long strip of paper and are automatically and successively fed between an anvil and a hammer with each pull of the trigger of the pistol.

The primary object of the invention is to provide a generally improved pistol of this class in which the general form of the pistol and the action of its parts shall simulate that of a regular automatic pistol, as well as one in which the action of the parts shall be positive, in which the feed of the fulminate strip shall be under complete and accurate control, and in which the general arrangement and combination of the parts will be simplified and improved.

A still further object is to provide an improved hammer and trigger and means for mounting the same whereby the liability to damage or disarrangement will be reduced to a minimum and a more easily operated repeating pistol will result.

A still further object is to provide an improved trigger for this class of pistols which by being extended beyond the trigger guard enables the same to be operated by two fingers instead of one and enables the same to be more easily operated without injury to the finger or liability of the latter to become pinched in between the free end of the trigger and the trigger guard as sometimes occurs with the ordinary short form of trigger arranged within and stopping short of the trigger guard.

A still further object is to improve the connection between the trigger and hammer whereby the latter will be moved or cocked against the resistance of the hammer spring by a direct pull of the trigger engaging on opposite sides of the hammer.

With the above mentioned and other ends in view, the invention consists in the novel construction, arrangement, and combination of parts, hereinafter described, illustrated in one of its embodiments in the accompanying

drawings, and more particularly pointed out in the appended claims.

Referring to the drawings, forming a part of this specification Figure 1, is a side elevation of the improved pistol, one side of the pistol body or casing being removed for the purpose of clearer illustration of the parts. Fig. 2, a central longitudinal sectional view showing the parts in their retracted positions just prior to the release of the hammer in the firing operation. Fig. 3, a vertical cross sectional view taken on line 3—3 of Fig. 1. Fig. 4, a rear view of the trigger and its mounting within the pistol body or casing. Fig. 5, a rear view of the hammer, detached, showing the fulminate strip actuating or feeding member carried thereby. Fig. 6, a cross sectional view of the hammer taken on line 6—6 of Fig. 1.

Similar numerals of reference designate like parts throughout all the figures of the drawings.

The improved toy pistol comprises a pistol body or casing preferably made up of two primary parts to form the barrel 1, and handle 2. The parts are preferably made of cast metal sections which when fastened together form a hollow chamber within which the working mechanism of the pistol is located.

The handle 2, is provided with a movable back 3, pivoted at its top between the side walls of the casing as at 3^a, to form an anvil 3^b, and provided at its bottom with a side extension 3^c, said side extension 3^c, being provided with a supporting pin 3^d, for carrying a roll of fulminate strip 4. By moving the back 3, rearwardly the roll of fulminate strip may be readily mounted upon or removed from the pin 3^d, and one end of the fulminate strip is adapted to be placed in front of the back 3, and to extend upwardly and over the anvil 3^b, and over which latter it is fed by the strip feeding mechanism carried by the hammer hereinafter described.

As a means for holding the fulminate strip 8, in frictional contact with the back 3, so as to prevent retrograde movement thereof in the movements of the hammer and feeding mechanism, a flat strip holding spring 5, is provided which spring 5, is mounted and held in position within the handle by means of pins 6, extending from the stationary portion of the handle, the free end of said spring bearing against the

fulminate strip between the anvil 3^b, and the roll carried upon the supporting pin 3^d.

The improved hammer comprises a hammer head 7, projecting upwardly and adapted to strike against the anvil 3^b, and a main body portion pivotally mounted between the side walls of the pistol body by means of laterally extending bearing pins or trunnions 7^a, which latter are mounted in suitable bearing openings in the side walls of the pistol body.

As a means for actuating the hammer against the anvil when moved and released by the trigger mechanism hereinafter described, a spring 8, is coiled about one of the trunnions 7^a, one end bearing against the stud 7^b, on the hammer body and the other end bearing against an abutment or stud 1^a, formed on one of the sections of the pistol body.

As a means for properly feeding the fulminate strip over and across the anvil during each working impulse or cocking movement of the hammer, the latter is provided with an extension portion 7^c, carrying a strip feeding spring member 8, said feeding spring 8, in the present instance, comprising a single length of wire bent upon itself forming a loop head 8^a, fitted in a notch 8^b, at the lower side of the extension 7^c, the sides of the spring forming spring arms normally resting against a cross bar 7^d, of the hammer extension, said spring arms being adapted to engage at opposite points on the fulminate strip in front of the back 3, as shown most clearly in Fig. 1, of the drawings and as the hammer is moved to its cocked position as shown in Fig. 2, it is obvious that the spring arms of the member 8, will move or feed the fulminate a requisite distance to bring the percussion cap upon the anvil 3^b, prior to the release of the hammer by the trigger hereinafter described.

As a means for operating the hammer a trigger 9, is provided said trigger 9, preferably comprising a single length of wire bent upon itself forming an operating loop 9^a, extending beyond and adapted to be guided by the trigger guard 10, and as a means for conveniently mounting the trigger one of the side members is bent about to form a bearing coil 9^b, which bearing coil 9^b, is adapted to be mounted upon a bearing pin 11, extending from one of the side sections of the pistol body.

As a means for actuating or returning the trigger to its initial or normal position a coiled spring 12, is provided, said coil spring 12, being mounted upon the bearing pin 11, one end 12^a, being adapted to engage one side of the trigger and the other end 12^b, engaging and bearing against a lug or abutment 13, formed integral with one of the side sections of the pistol body, and as a means for holding the end 12^b, in proper

assembled position and particularly as against lateral creeping or displacement a securing stud pin 14, extends from and is carried by the opposite pistol section, the end of said stud pin bearing against the end 12^b, of the spring as shown most clearly in Figs. 1 and 2 of the drawings.

As a means for alternately engaging and moving and releasing the hammer in the operation of the same through the trigger said hammer is provided on opposite sides with oppositely arranged beveled shoulders 7^e, adapted to be alternately engaged and released by the laterally movable spring arms 9^c of the trigger said arms straddling or extending on opposite sides of the web portion of the hammer carrying the beveled shoulders 7^e, as shown. As the trigger is drawn rearwardly in the cocking movement of the hammer the arms 9^c, are in engagement with and ride upon the shoulders 7^e, the hammer and trigger being moved against the resistance of the respective springs 8, and 12, and when the hammer and trigger are moved to a position slightly beyond that indicated in Fig. 2, the arms 9^c, will snap beneath the shoulders 7^e, to permit the hammer to be released and strike against the anvil in the firing operation. When pressure is released upon the trigger, the latter is returned through the agency of the arm 12^a, of the spring 12, and in so doing the laterally movable arms 9^c, are caused to ride upon and move over the beveled portions of the shoulders 7^e, after which they will snap inwardly into engagement with the shoulders in the repeating or successive firing operation.

From the foregoing description, taken in connection with the accompanying drawings, the operation and advantages of my invention will be readily understood.

Having thus described one of the embodiments of my invention, what I claim and desire to secure by Letters Patent is,

1. In a toy pistol, a hammer provided with a pair of strip feeding spring members.

2. In a toy pistol, the combination with a pistol body provided with a trigger guard and a spring resisted hammer therein; of a spring resisted trigger pivotally mounted therein and comprising a single length of wire bent to form a handle loop extending beyond and surrounding said trigger guard.

3. In a toy pistol, the combination with a pistol body including a pivoted back having an anvil at its top; of a fulminate strip holding spring bearing against said back, and a pivoted hammer provided with a pair of spring arms adapted to bear against said back above said fulminate strip holding spring and to feed said fulminate strip with the actuation of said hammer.

4. In a toy pistol, a pistol body provided with a trigger guard, a pivoted spring resisted hammer having oppositely disposed

laterally extending inclined shoulders, and a spring resisted trigger comprising a pivoted movable member extending beyond and about said trigger guard and having laterally movable spring arms adapted to cooperate with said inclined shoulders of said hammer whereby to cock the latter when the trigger is pulled, said spring arms being adapted to pass beneath said shoulders to release the hammer and when said trigger is returned to ride upon said inclined shoulders and reengage with the latter for the repeating operation.

5. A toy pistol, comprising a pistol body including a pivoted back having an anvil and a roll of fulminate strip extending in front of said back and anvil, a spring bearing against said strip between said roll and anvil, a spring resisted pivoted hammer provided with oppositely arranged beveled shoulders, a fulminate strip feeding spring carried by said hammer, a trigger having laterally movable arms engaging and riding upon said shoulders during the cocking movement of said hammer and adapted to pass beneath said shoulders to release said hammer when said trigger is fully retracted, and a spring for returning said trigger and causing said laterally movable arms to ride over the beveled portions of said shoulders and snap into engagement with the latter when the trigger is returned to its normal or initial position.

6. A toy pistol, comprising a pistol body including a handle provided at its top with an anvil and at its bottom with a roll of fulminate strip extending toward said anvil, a strip holding spring between said roll and anvil, a pivoted spring resisted hammer having a webbed body provided on either side with beveled shoulders, a pair of spring arms carried by said hammer and engaging said strip between said roll and anvil, a pivoted trigger comprising an operating loop terminating in laterally movable arms straddling said webbed body and normally engaging said shoulders whereby to cock the hammer when the trigger is pulled and adapted to pass beneath said shoulders to release the hammer, and a spring engaging said trigger to return the latter and cause said spring arms to ride over the beveled portions of said shoulders and reengage with the latter for the repeating operation.

55 7. A toy pistol, comprising a pistol body provided with an anvil at its top rear portion, a roll of fulminate within said pistol body and extending to and over said anvil, a spring having its free end bearing against said strip between said roll and anvil, a spring resisted hammer having oppositely disposed beveled shoulders above its pivoted portion, a strip feeding spring carried by said hammer and provided with spring arms bearing against said strip above said strip

holding spring, and a spring resisted trigger provided with laterally movable arms co-operating with said beveled shoulders whereby to cock the hammer when the trigger is pulled and passing beneath said shoulders to release the hammer and whereby when the trigger is released said laterally movable arms will ride over the beveled portions of said shoulders and reengage with the latter for the repeating operation.

8. A toy pistol, comprising a pistol body including a pivoted handle back provided with an anvil at one end and carrying a roll of fulminate strip at the other, a strip holding spring bearing against said back between said roll and anvil, a pivoted spring resisted hammer provided with oppositely disposed beveled shoulders above its pivoted portion, a pair of spring arms carried by said hammer and adapted to engage and feed said fulminate strip, and a spring resisted trigger provided with laterally movable arms normally engaging said shoulders whereby to cock the hammer when the trigger is pulled, said trigger being so pivoted relative to the pivoted portion of said hammer as to cause said laterally movable arms to pass beneath said shoulders when the trigger is drawn to its rearward position whereby the hammer is released and whereby as the trigger is returned to its normal or initial position said laterally movable arms will be caused to ride over the beveled or inclined portions of said shoulders and reengage with the same for the repeating operation.

9. In a toy pistol, a pistol body, a pivoted spring resisted hammer having oppositely disposed laterally extending shoulders, and a spring controlled trigger having arms adapted to coöperate with said shoulders whereby to cock said hammer when the trigger is pulled and passing therefrom to ride over said shoulders and reengage with the latter when the trigger is returned to its normal or initial position.

10. In a toy pistol, a pistol body, a spring resisted pivoted hammer having oppositely disposed laterally extending inclined shoulders, and a spring controlled divided trigger coöperating with said inclined shoulders of said hammer whereby to cock the latter when the trigger is pulled and to ride upon and pass from said shoulders to release the hammer when said trigger is moved to its rearward position and upon the return of said divided trigger the latter will ride over the beveled portions of said shoulders and reengage with the latter for the repeating operation.

11. In a toy pistol, a pistol body provided with a handle having an anvil, a pivoted spring resisted hammer provided with fulminate strip feeding mechanism at one side and having a pivoted web portion at the

other said web portion being provided with oppositely disposed inclined shoulders, and a spring controlled trigger having arms normally engaging said shoulders whereby to 5 cock the hammer when the trigger is pulled and passing therefrom upon the release of said hammer being adapted upon the return of the trigger to ride over said shoulders and reengage with the latter for the repeating 10 operation.

12. In a toy pistol, a pistol body including a handle back provided with an anvil, a fulminate strip in front of said back and anvil, a spring resisted pivoted hammer provided with strip feeding mechanism adapted 15 to coöperate with said back and anvil, said hammer being provided on opposite sides and above its pivoted portion with inclined beveled shoulders, and a spring controlled 20 divided trigger straddling said hammer and normally engaging said shoulders whereby to cock the hammer when the trigger is pulled and when released to ride upon said beveled shoulders and reengage with the latter 25 for the repeating operation.

13. In a toy pistol, the combination with a pistol body provided with a trigger guard;

of a spring resisted trigger extending to and guided by said trigger guard.

14. In a pistol, the combination with a 30 pivoted spring actuated hammer; of a spring resisting trigger comprising a single length of wire bent upon itself forming pivoted spring arms alternately moving toward and from each other whereby to engage and release said hammer as said trigger is returned to and drawn from its initial or normal position.

15. In a pistol, a pistol body, a spring actuated hammer, a spring controlled trigger 40 having arms arranged in coöoperative relation to said hammer and alternately engaging and releasing the same whereby to cock the hammer when the trigger is pulled and when the trigger is returned to reengage 45 with said hammer for the repeating operation.

In testimony whereof I have affixed my signature in presence of two witnesses.

ROSCOE BEAN.
